WATER-SERVICE DEVICE

John T. McGarry and Howard A. Eads, Cincinnati, Ohio; said Eads assignor to said McGarry

Application May 23, 1942, Serial No. 444,286

12 Claims. (Cl. 137—21)

This invention relates to a water service device, and more specifically to a structure commonly known as a water column, the function of which is to serve boiler water to a reservoir or tank ordinarily carried by the tender of a steam locomotive.

One of the objects of the invention is to provide structural improvements in a water column, in the interests of simplicity, durability, safety, and reduction of costs in manufacture and maintenance.

Another object of the invention is to provide in a water column, novel means to facilitate and expedite normal usage of the device, in order to avoid unnecessary effort and delay in the running schedule of trains.

A further object is to provide a water column possessing the stated advantages, with provision made also for an increased delivery rate of water to the tank of the locomotive tender, utilizing existing sources of water supply serving the water column.

Another object is to provide in a water column of the improved type disclosed herein, means which are effective, safe, and durable, for locking the delivery spout against kick-up as the water valve is opened initially to serve the tender.

Another object is to structurally improve a water column in such manner as to effectively withstand heavy strains and abuses, and those elements of nature such as ice, snow, water, dust and intense heat, which might be expected to disable exposed mechanisms or devices of the general character herein disclosed.

The foregoing and other objects are attained by the means described herein and disclosed in the accompanying drawing in which:

Fig. 1 is an elevational view, partly in cross section showing a water column embodying the present invention.

Fig. 2 is an enlarged cross sectional view taken on line 2—2 of Fig. 1.

Fig. 3 is a plan view of a lock bar for the delivery spout.

Fig. 4 is a perspective view of a clutch element for the lock bar, utilized in the improved structure.

Fig. 5 is a fragmental end view of the nozzle of a gooseneck conduit illustrated by Fig. 1.

Fig. 6 is a detail view of a modified form of valve rod and clutching assembly.

Like the water columns presently in use, the water column of this invention is adapted for placement alongside a railway track, in position

for swinging movement of its delivery spout from a normally inoperative elevated position parallel to the track, to an operative position substantially at right angles to the track, with the delivery spout lowered over a locomotive tender and in registry with the water hole thereof. In the inoperative position of the delivery spout, the structure preferably is held against accidental swinging movement, as will be explained; while in the operative position the spout is to be locked against kick-up resulting from delivery of water thereto by the nozzle of the standpipe, or of the gooseneck conduit which forms part of the standpipe. The foregoing general statements will be amplified as the description proceeds.

In accordance with the teaching of the present disclosure, the water column includes a tall rigid tower consisting of three or more uprights 7 having their lower ends securely bolted or otherwise fixed as at 8 to the pit structure 9 which houses the main valve 10 controlling the flow of water through the apparatus. At the upper ends of the uprights, the rigid tower carries a top cap 12 which is fixed as at 13 to the uprights. The top cap furnishes a base upon which may be rotated an elevated turntable indicated generally by the character 14. The top cap and the turntable are located at an elevation well beyond the reach of workmen concerned with operation of the water column, and the elevation of the turntable may approximate the height of a locomotive tender in the vicinity of a water hole in the tank or reservoir.

As illustrated by Figs. 1 and 2, the turntable 14 may be in the form of a casting having a vertical bore 15 through which may extend the upper end portion 16 of a straight vertical standpipe 17, the lower end 18 of which standpipe extends through an aperture 19 in the top of the pit, where said lower end is fixed as at 20 to the outlet port of the main valve 10. At 21 is indicated a swivel union between the inlet port of the valve and an adjacent portion of the water main 22, which supplies water to the valve, the swivel union being provided for the purpose of permitting bodily rotation of the valve and the standpipe while at the same time maintaining a fluid tight relationship thereof to the supply pipe. The valve may include a suitable lever 23 operating about a pivot shaft 24 to effect opening and closing movements of the valve. In the form of valve illustrated herein, partial rotation of lever 23 in a clockwise direction serves to open the valve. As shown in Fig.

1 the lever is lowered, indicating that the valve is closed.

With further reference to the turntable 14, and especially to the illustration of Fig. 2, it should be noted that the turntable is provided with at least two outwardly extending brackets 25—25 providing bearings for the axles 26 of the rollers 27 which provide for substantially frictionless rotation of the turntable relative to the stationary cap 12. The upper surface 28 of the cap is developed into an annular track to support the rollers as the turntable rotates with the standpipe. Unitary rotation of the turntable with the standpipe may be effected in any approved manner. For this purpose, the set screws 29 threaded into the material of the turntable, are adapted to butt against the outer surface of the standpipe, which suggestion is illustrative of one simple arrangement for securing the standpipe to the turntable for rotation therewith. The characters 30 indicate strengthening ribs for the roller bearing brackets.

In order that the overhanging weight of the structure may not dislocate the standpipe from a vertical position, means are provided for the lateral support of either the turntable or the standpipe. While the track for the rollers might readily be designed to furnish such lateral support, as in our copending application of even date, the alternative structure illustrated herein might be utilized for the purpose. Said alternative structure consists in providing the top cap with a rather large bore 31 providing an annular smooth wall, against which may ride the annular flange 32 that forms an integral part of and extends radially from the turntable. The contacting surfaces of the annular bearing 31—32 may be provided with lubricating means, or with other suitable means for reducing friction, if desired.

The flange 32 preferably is cut away as at 33 and 34, to accommodate a pair of vertical reciprocable valve rods 35—36 which are exposed exteriorly of the upright standpipe 17, at opposite ends of a diameter thereof. The lower ends of these valve rods are to be pivotally connected with levers such as 23 at opposite sides of the valve, one of said pivots being illustrated at 37 of Fig. 1. A guide in the form of a perforated extending lug 38 may be furnished in the vicinity of the valve, to support each exposed valve rod.

As will be evident from Fig. 2, the valve rods 35 and 36 are within the area defined by the bore 31 of the top cap 12, so that the rods may move through a complete circle when the turntable is rotated along with the standpipe and valve 10.

Upon the upper end of standpipe 17, there is fixedly mounted, by means of a flange connection 39 or otherwise, a top section of standpipe indicated generally by the character 40, and which is preferably in the form of a gooseneck conduit. The curvature of the gooseneck conduit is made quite large, and circular, so that it will offer but little resistance to a high velocity flow of water directed thereto by the standpipe, the terminal end of the gooseneck conduit being open at 41 to provide a nozzle for directing the flow generally outwardly and downwardly of the structure. At a location near the nozzle, but at a limited distance therefrom, a pair of oppositely extending bosses 42 may be furnished, including pivots 43 to support a delivery spout 44 that is movable about the pivots in a vertical plane, from the full line inoperative position of Fig. 1, to the broken line operative and lowered position indicated upon the same drawing figure. The bosses

42—42 may be formed integrally with the gooseneck conduit, or as separate parts attached thereto, as desired.

As the delivery spout preferably is constructed of sheet metal, it may advisedly be reinforced at its inner or receiving end, by a circumferential heavy metallic strap or hoop 45 riveted or otherwise secured thereto, and provided with bearing means 46 for reception of the pivot shafts or studs 43. The reinforcing means 45 may be of any desired shape or material, so long as it will withstand the strain resulting from grasping the outer end of the delivery spout and rotating the turntable and the standpipe parts 17 and 40, through the connections at 43—46. The character 47 indicates one of a pair of loops or handles fixed to opposite sides of the delivery spout in position to be contacted by a fireman's hook or other implement that may be used in swinging the spout about the axis of the standpipe 17.

At locations on the gooseneck conduit remote from the pivots 43, a pair of oppositely extending stops or abutments 48 may be provided, either integrally with the gooseneck conduit or as separate parts fixed thereto, to serve as limiting means for the weights 49 of a counterbalance structure for the delivery spout. The counterbalance structure may consist of a pair of rearwardly extending arms 50 fixed to the delivery spout by means of rivets, bolts or other fasteners 51, so extended along opposite sides of the gooseneck conduit as to locate the pair of weights 49 directly over and upon the stops when the delivery spout is in the full line elevated position of Fig. 1. It may be stated that the weights 49 are adjustable along the counterbalance arms, for obvious reasons.

From the foregoing explanation, it should be at once evident that normal usage of the water column involves grasping the outer end of the delivery spout 44 to rotate it, with the turntable 14 and the standpipe parts 17 and 40 until the spout assumes a position substantially at right angles to a railway track, whereupon the spout may be lowered to the broken line position of Fig. 1 by rotating it about its pivots 43—43 until the delivery end 52 of the spout registers with the water hole of a locomotive tender to be supplied with water from the water column. Having so positioned the delivery spout, an attendant is required to open the valve 10, which he does by pulling a rope, chain, cable, or the like 53 having operative connection with the valve through the vertically reciprocable valve rods 35 and 36. It is convenient to tie one end of the element 53 to the handle of the spout as indicated at 54, the opposite end being tied as at 55 to the free end of a valve rod actuating lever 56.

The mounting means for the valve rod actuating lever 56 may be constituted of one or more extending brackets 57 located upon the gooseneck conduit above the flange 39, said bracket being properly bored to provide bearings for a shaft 58 that carries a fixed socket 59 in which the lever 56 is secured. Opposite ends of shaft 58 may have fixedly mounted thereon a pair of arms 60, disposed adjacent to each of the valve rods, and pivotally connected thereto at the locations 61. With the levers 60 and 56 fixed to the shaft 58 as explained, it will be understood that a pull applied to the flexible element 53 will rotate the lever assembly 56—60 as a bell crank at the pivotal point 58, to elevate the pair of valve rods in unison for opening the valve. Although but one lever such as 60 is illustrated by the drawing, it will be under-

stood that another such lever would be seen at the rear of the structure illustrated by Fig. 1. The valve 10 being of the self-closing type, water will flow through it only so long as an attendant exerts a pull upon the flexible element 53.

When the delivery spout is disposed to the operative position illustrated by the broken lines of Fig. 1, and water in a forceful stream is directed into it from the nozzle 41, the force of the water striking the down turned delivery end of the delivery spout tends to produce a forceful up-kick of the spout, and at times this up-kick reaction is of such magnitude as to injure an attendant standing upon the locomotive tender, or to dislodge him therefrom. In order to obviate the kick-up reaction of the spout, the apparatus of this invention is provided with a spout lock which is so associated with the valve actuator assembly that the valve may not be opened without simultaneous locking of the spout in its lowered operative position. Such spout lock may comprise a forked element indicated generally by the character 63, which is shown in the detailed view of Fig. 3, and which will hereinafter be referred to as the locking bar. At the forward end of the locking bar, a pivotal connection 64 is made with a fixed bracket 65 of the delivery spout. The opposite end of the locking bar is forked to provide the arms 66, which are toothed or serrated along corresponding edges thereof to simulate spaced parallel racks. The racks are located at opposite sides of the gooseneck conduit, and each one overlies one of the vertical valve rods and its associated lever 60. At a location above the racks, a seat 67 may be furnished upon the gooseneck conduit to mount a clutch element indicated generally at 68 and illustrated in detail by Fig. 4. This clutch element may consist of a crossbar having depending ends 69 properly rounded and provided with teeth 70 corresponding to the rack teeth of the locking bar, so that by the act of elevating the racks against the teeth of the clutching element, the racks will be locked against longitudinal reciprocation. Normally, the racks of the locking bar are supported by means of the levers 60 for free reciprocating movement out of mesh with the teeth of the clutch element 68, so that free vertical adjusting movements of the delivery spout are possible. When the actuating lever 56 is moved, however, to lift the valve rods for opening the valve, the rack teeth will be forced into engagement with the teeth of the clutch element, thereby to lock the delivery spout against vertical movement in either direction.

For the purpose of so placing the rack teeth of the clutch element, each of the levers 60 may carry a suitable bracket 71 which may carry a support 72 along which the smooth lower edges of the racks may slide as long as the valve rods are in the lowered valve-closing position. The elements 72 may be in the form of rollers, if desired. As will be understood, the lift of the valve rods is sufficient to elevate the rack portions of the locking bar into engagement with the teeth of the clutch element. Thus, whenever the flexible element 53 is pulled for rocking the assembly 56-60 in clockwise direction about the shaft 58, the locking of the delivery spout will be effected substantially concurrently with opening of the supply valve. The brackets 71 preferably are so formed as to embrace the sides of the racks, and to thereby keep the racks aligned with the toothed ends of the clutch element.

In Fig. 6 is illustrated an alternative form of valve actuator assembly, wherein the levers 156 75

and 160 correspond to the levers 56 and 60 of Fig. 1, the lever 160 having a clamp end 75 closed upon the valve rod by means of a clamp screw 76 at a point removed from the upper end of the valve rod, so that said upper end may mount a bifurcated bracket or clevis 77 serving as a bearing to support a rotatable wheel 78. The wheel 78 may have its periphery 79 flanked by a pair of flanges between which the rack portion of the locking bar may rest and be guided in its longitudinal reciprocatory movements. An axle for the wheel is indicated at 80, and an adjustment means for establishing a proper elevation of the wheel may be provided upon the upper end of the valve rod by furnishing the valve rod with threads 81 and a lock nut 82 to abut the clevis, which of course is threaded onto the upper end of the valve rod. It will readily be evident that the lever assembly of Fig. 6, when rocked in clockwise direction upon the shaft 58, will elevate the wheel 78 and the locking bar supported thereby, to dispose the rack teeth in substantial engagement with the corresponding teeth of the clutch element. The delivery spout will thereby be locked against vertical movements in substantially the manner explained in connection with Fig. 1.

Referring to the top cap 12 of the stationary tower, it will be observed that a depression 83 in the track for the rollers 27 is shown, the depression being duplicated at opposite ends of a diameter of the top cap. The purpose of the depressions or inclines 83, is to urge the turntable to a home position at which the delivery spout is in parallelism with the railway track, whenever the spout is swung to a position of near parallelism with the track. The slight vertical movement of the standpipe 17 resulting from the turntable rollers entering the depressions, may be taken up in the swivel union 21, or elsewhere in the assembly, as, for instance, in the connection between the turntable and the standpipe 17. In place of the indicated depressions, the turntable might alternatively be provided with a positive lock of the kind disclosed in our said copending application.

As stated in the introductory portion of the specifications, the structural improvements in the herein-described water column are inducive of simplicity of manufacture and operation, as well as to a substantial increase in durability and length of trouble-free service. These advantages are not currently inherent in kindred devices, presently known and used, wherefore it should readily be evident that the improvements in structure herein taught are of substantial merit, and constitute a commendable advancement of the art.

It should be appreciated that the nozzle end of the gooseneck conduit preferably is at a minimum elevation, at least as low as the roof of the average railway freight car so that advantage may be had of the greatest possible head of water obtainable from a storage tank or other source of supply feeding the pipe 22 within the pit. Since in the majority of railway water systems, the water column is supplied from an elevated storage tank of great capacity, it is desirable to reduce the height of the gooseneck conduit as much as possible in order to secure the maximum pressure and flow of water at the nozzle 36. The reduction in the height of the nozzle requires that the delivery spout be upwardly inclined as illustrated by the full lines in Fig. 1, with the delivery end of the spout normally elevated sufficiently to clear the rail-

way car roofs and the buckboards of the largest locomotive tender. By means of this construction, there is obviated the likelihood of a passing train striking and damaging the water column even though the spout be swung toward the track accidentally, because the spout is normally maintained in the inclined inoperative position by means of its counterbalance, regardless of rotation of the turntable. A positive and deliberate force is required in placing the delivery spout to any lowered position at which it might be struck by a passing train.

It is to be understood that various modifications and changes in the structural details of the device may be made, within the scope of the appended claims, without departing from the spirit of the invention.

We claim:

1. In a railway water column or the like, the combination of a tower having a top portion elevated beyond the reach of an attendant, and a lower portion adapted for fixation to a pit structure, a turntable mounted for rotation upon the top portion of the tower, a standpipe supported by the turntable for rotational movement therewith, and including a nozzle portion for directing a flow of fluid into a delivery spout, said standpipe extending into the pit structure with the tower in protective relationship therewith, a delivery spout having a receiving end and a delivery end, means pivoting the receiving end of said spout to the nozzle portion of the standpipe for movement of the delivery end of the spout vertically to elevated and lowered positions, a locking bar pivoted to the delivery spout in depending relationship thereto, and having a free end directed toward the turntable, means movable bodily with the turntable to clutch the locking bar and establish a fixed condition of the delivery spout angularly to the standpipe, and means for actuating said clutch means concurrently with supplying water under pressure to that end of the standpipe which is disposed within the pit structure.

2. In a railway water column or the like, the combination of a tower having a top portion, and a lower portion adapted for fixation to a pit structure, a turntable mounted for rotation upon the top portion of the tower, a standpipe supported by the turntable for rotational movement therewith, and including a nozzle portion for directing a flow of fluid into a delivery spout, said standpipe extending into the pit structure with the tower in protective relationship therewith, a delivery spout having a receiving end and a delivery end, means pivoting the receiving end of said spout to the nozzle portion of the standpipe for movement of the delivery end of the spout vertically to elevated and lowered positions, a locking bar depending downwardly from the delivery spout and extending toward the standpipe, and means selectively operative to clutch the locking bar and establish a fixed condition of the delivery spout angularly to the standpipe.

3. In a railway water column or the like, the combination of an apertured pit structure and a tower fixed in upstanding relationship to the pit structure and about the aperture thereof, a top cap on the tower including a circular track in a substantially horizontal plane, a turntable above said cap, and roller means on the turntable to rest upon said circular track for support of the turntable during rotation of the latter, said turntable having a central opening, a

standpipe extending vertically through said central opening and projecting downwardly into the aperture of the pit structure, a supply valve in the pit structure for control of fluid directed upwardly into the standpipe, means on the turntable to support the standpipe and enforce rotation of the standpipe with the turntable, a gooseneck conduit mounted for rotation with the turntable and having a nozzle for directing a flow of fluid from the standpipe downwardly and outwardly of the axis of rotation of the turntable, a delivery spout having an outer delivery end and an inner receiving end, the latter end being receptive of fluid discharging from the nozzle of the gooseneck conduit, and means on the gooseneck conduit for supporting the inner receiving end of the delivery spout pivotally, to guide the spout vertically along an arcuate path of movement from an upwardly inclined inoperative position to a downwardly inclined operative position, means including a valve rod extending along the exterior of the standpipe through the aperture of the pit structure, for controlling the opening and closing movements of the valve, said valve rod being within the protective interior of the tower throughout substantially the full length of the rod, and means movable with the valve rod for locking the delivery spout against movement about its pivotal support upon the gooseneck conduit, at various inclinations of said spout.

4. In a railway water column or the like, the combination of an apertured pit structure and a tower fixed in upstanding relationship to the pit structure and about the aperture thereof, a supply valve within the pit structure, an upright standpipe having a lower end projected through the aperture aforesaid and having a fluid communicating relationship with the valve, said standpipe being surrounded by the tower substantially throughout the height of the standpipe, a rotatable turntable atop the tower and means securing the standpipe to the turntable for rotation therewith, a nozzle element fixed to the upper end of the standpipe and arranged to direct a stream of water laterally therefrom, an adjustable delivery spout supported on the nozzle element in position to guide the stream to a receptacle, an upright reciprocable valve rod extending along the standpipe exteriorly thereof, and through the aperture of the pit structure, said rod having an operating connection with the valve and being surrounded and protected by the tower throughout substantially the full height of the valve rod above the pit structure aperture, an actuating lever pivoted to said rod, the lever being in turn pivoted upon the nozzle element, whereby pivotal movement of the lever lifts the rod for controlling the valve, a movable locking bar depending from the delivery spout and having an end portion adapted to be clutched for fixing the position of the spout, means on the actuating lever near the pivotal point of the rod, for supporting the locking bar as the inclination of the delivery spout is adjusted, and a stationary clutch member located upon the nozzle element directly above the locking bar, including means to grasp and hold the end portion of said bar incident to elevating movements of the valve rod and the locking bar support of the actuating lever.

5. In a railway water column or the like, the combination of a standpipe having upper and lower ends, a water control valve in fluid communicating relationship with the lower end of the standpipe, a gooseneck conduit at the upper

end of the standpipe, and a hollow adjustable delivery spout supported pivotally upon the gooseneck conduit to receive a stream of water from the nozzle and to direct said stream toward a receptacle, a locking bar carried by the delivery spout, a vertically reciprocable valve rod having at one end an operative connection with the valve to open and close the latter, said rod being disposed wholly exteriorly of and in parallelism with the standpipe, and substantially coextensive therewith, the opposite end of said valve rod having associated therewith a member to normally support the weight of the locking bar, and means to clutch and release the locking bar as the valve rod is vertically reciprocated in opposite directions.

6. In a railway water column or the like, the combination of a standpipe having upper and lower ends, a water control valve in fluid communicating relationship with the lower end of the standpipe, a gooseneck conduit at the upper end of the standpipe, and a hollow adjustable delivery spout supported pivotally upon the gooseneck conduit to receive a stream of water from the nozzle and to direct said stream toward a receptacle, a locking bar carried by the delivery spout, a vertically reciprocable valve rod having at one end an operative connection with the valve to open and close the latter, said rod being disposed wholly exteriorly of and in parallelism with the standpipe, the opposite end of said valve rod having associated therewith a member to normally support the weight of the locking bar, and a clutching element for the locking bar, disposed for engagement and disengagement with the locking bar as the member supporting the weight of the locking bar is shifted by the valve rod toward and from the clutching element.

7. In a railway water column or the like, the combination of a standpipe having upper and lower ends, a water control valve in fluid communicating relationship with the lower end of the standpipe, a gooseneck conduit fixed at the upper end of the standpipe, and a hollow adjustable delivery spout arranged to receive a stream of water from said conduit and to direct said stream toward a receptacle, a rigid fixed tower surrounding the standpipe in protective relationship thereabout, said tower including a top portion disposed at a substantial elevation approximating the height of the upper end of the standpipe where the latter meets the gooseneck conduit, a turntable rotatable upon the top portion of the tower, pivot means near the exit of the gooseneck conduit supporting the adjustable delivery spout for arcuate movement in a vertical plane, means fixing the upper end of the standpipe to the turntable for rotation therewith, and a vertically reciprocable valve rod disposed exteriorly of the standpipe along the full length of the latter, said valve rod having an operative connection with the valve at its lower end, actuating means near the opposite end of the valve rod for imparting vertical movements thereto and operating said valve to open and closed positions, a locking bar support on said actuating means and movable with the valve rod, a locking bar having a toothed end resting on said support, and an opposite end pivoted upon the delivery spout, a fixed clutching element overlying the toothed end of the locking bar at an elevation such that the bar clears the clutching element when the valve rod is lowered during adjusting movements of the delivery spout, whereas ele-

vating of said valve rod serves to force the toothed end of the locking bar into clutching engagement with the overlying clutching element.

8. In a railway water column or the like, the combination of a standpipe having upper and lower ends, a water control valve in fluid communicating relationship with the lower end of the standpipe, a gooseneck conduit fixed at the upper end of the standpipe, and a hollow adjustable delivery spout arranged to receive a stream of water from said conduit and to direct said stream toward a receptacle, a rigid fixed tower surrounding the standpipe in protective relationship thereabout, said tower including a top portion disposed at a substantial elevation approximating the height of the upper end of the standpipe where the latter meets the gooseneck conduit, a turntable rotatable upon the top portion of the tower, means on the gooseneck conduit supporting the adjustable delivery spout for arcuate movement in a vertical plane, means fixing the upper end of the standpipe to the turntable for rotation therewith, and a vertically reciprocable valve rod disposed exteriorly of the standpipe along the full length of the latter, said valve rod having an operative connection with the valve at its lower end, means near the opposite end of the valve rod for imparting vertical movements thereto and operating said valve to open and closed positions, and means operating concurrently with movements of the valve rod, for locking the delivery spout to the gooseneck conduit.

9. In a railway water column or the like, the combination of a standpipe having upper and lower ends, a water control valve in fluid communicating relationship with the lower end of the standpipe, a gooseneck conduit fixed at the upper end of the standpipe, and a hollow adjustable delivery spout including a delivery end and a receiving end, to receive a stream of water from said conduit and to direct said stream toward a receptacle, pivot means near the exit of the gooseneck conduit supporting the receiving end of the delivery spout for arcuate movement of the spout in a vertical plane, a rigid fixed tower surrounding the standpipe in protective relationship thereabout, said tower including a top portion, and a turntable rotatable upon the top portion of the tower, means fixing the upper end of the standpipe to the turntable for rotation therewith, a reciprocable operating rod associated with the valve and extending upwardly beyond the turntable, a locking bar support near the upper end of the valve operating rod for reciprocation therewith, a locking bar having a free end resting upon said support, and another end non-rigidly connected to the delivery spout, whereby reciprocatory movements of the valve operating rod serve to swing the locking bar relative to the spout, a clutch element to grip and hold the locking bar upon each movement of the valve operating rod in one direction, thereby to fix the inclination of the spout, whereas movement of said rod in the opposite direction frees the locking bar for movement along the support as the spout pivots relative to the gooseneck conduit.

10. In a railway water column or the like, the combination of a rotatable standpipe including valve means at its lower end for the control of fluid flowing into the standpipe, a gooseneck conduit on the standpipe having an exit nozzle at one end, pivot means near the exit nozzle of the

gooseneck conduit, and a delivery spout having a receiving end journaled upon said pivot means for adjustment of said spout arcuately in a vertical plane, a locking bar having a forked end to straddle the gooseneck conduit, and an opposite end non-rigidly fixed to the delivery spout remote from the receiving end thereof, whereby arcuate movement of the spout induces advancement and retraction of the forks of the locking bar past the gooseneck conduit, a valve actuator, a clutching element, and means operative upon manipulation of the valve actuator to selectively place the forks of the locking bar in clutching relationship with the clutching element.

11. In a railway water column or the like, the combination of a rotatable standpipe including valve means at its lower end for the control of fluid flowing into the standpipe, a gooseneck conduit of approximate half-circle configuration having an exit nozzle at one end, and means at the opposite end for attachment of the gooseneck conduit to the top of the standpipe, with the major portion of the body of the gooseneck conduit disposed to one side of the vertical axis of the standpipe, pivot means near the exit nozzle of the gooseneck conduit, and a delivery spout having a receiving end journaled upon said pivot means for adjustment of said spout arcuately in a vertical plane, a counterbalance arm fixed directly upon the delivery spout to extend rearwardly thereof past the pivot means and beyond the vertical axis of the standpipe, a weight on said arm to counterbalance the weight of the delivery spout, said weight being located at that side of said vertical axis which is opposite to the direction of outward extension of the delivery spout, actuating means for the fluid control valve, and releasable means to lock the delivery spout in one of several positions of adjustment when the control valve is opened.

12. In a railway water column, or the like, the combination of an apertured pit structure and a tower fixed about the aperture thereof, a top cap on the tower including a circular track, and a turntable including roller means to rest upon said track, said turntable having a central opening, a standpipe extending vertically through said central opening and projecting into the pit aperture, a valve in the pit structure, means on the turntable to support and enforce rotation of the standpipe with the turntable, a gooseneck conduit rotatable with the turntable and having a nozzle, a delivery spout having an end receptive of fluid discharged from the nozzle, means on said conduit for pivotally supporting said end of the delivery spout, to guide the spout vertically along an arcuate path of movement, means including a valve rod extending along the exterior of the standpipe and through the pit aperture, for controlling the valve, said valve rod being within the protective interior of the tower throughout substantially the full length of the rod, an actuator for the valve rod including a lever pivoted at one end upon the gooseneck conduit, and having its opposite end attached to said rod, a movable locking bar depending from the delivery spout and having an end portion adapted to be clutched for fixing the position of the delivery spout, means on the actuator lever for supporting the aforementioned end portion of the locking bar as the inclination of the delivery spout is adjusted, and a clutch element located upon the gooseneck conduit in position to grasp the locking bar when the latter is moved into contact therewith incident to elevating movements of the valve rod and the locking bar support of the actuator lever.

JOHN T. McGARRY.
HOWARD A. EADS.
